UNITED STATES PATENT OFFICE.

DOMENICO MOLINARI, OF SEATTLE, WASHINGTON.

NON-REFILLABLE BOTTLE.

1,286,387.

Specification of Letters Patent.

Patented Dec. 3, 1918.

Application filed June 4, 1918. Serial No. 238,073.

To all whom it may concern:

Be it known that I, DOMENICO MOLINARI, citizen of the United States, residing at Seattle, in the county of King and State of Washington, have invented certain new and useful Improvements in Non-Refillable Bottles, of which the following is a specification.

This invention relates to improvements in non-refillable bottles and has for its principal object to provide an improved and novel construction in non-refillable bottles, especially adapted for use in connection with the heavier liquids such as catsup, syrups and the like; it being understood of course that it can be used in connection with fluids of any consistency but more especially adapted to the thicker fluids; to provide a double construction bottle in which a cap is united integrally with the bottle.

Other objects will appear as my invention is more fully explained in the following specification, illustrated in the accompanying drawings, and pointed out in the appended claim.

In the drawings Figure 1 is a plan view of my bottle. Fig. 2 is a vertical section of same.

Referring more particularly to the drawings numeral 1 indicates an outer bottle and 2 an inner bottle arranged concentrically with the outer bottle and integral therewith at the bottom 3. Both bottles are open at the top and after being filled a cap 4 is fitted over the mouth of the bottle 1 and cemented to the top of said bottle with a liquid glass flux of any approved kind. Within the cap 4 an elongated and globular shaped stopper 5 is positioned to seal the inner bottle 2 within which the contents of the bottle is normally retained. An outer cork 6 closes the opening in the cap 4 and holds the stop-

per 5 in seated position thus preventing the contents of the bottle from getting out into the space between the inner and outer bottles 45 where it would be readily noticeable. When the cork 6 is removed and the stopper 5 pulled up by an extension 5^a the contents of the bottle may be poured out past the stopper. If an attempt is made to refill the bottle some or all of the filling will get between the bottles and thus defeat the object of refilling. 50

While I have shown a particular form of embodiment of my invention, I am aware 55 that many minor changes therein will readily suggest themselves to others skilled in the art without departing from the spirit and scope of the invention, and I therefore desire to avoid being limited to the exact 60 form shown and described.

Having described my invention what I claim as new and desire to protect by Letters Patent, is:—

In a device of the class described the combination of an outer bottle, an inner bottle concentric with the said outer bottle, a cap which fits over the mouths of both bottles and is integrally connected to the outer bottle, a stopper positioned within the cap and 65 normally closing the inner bottle, an extension on the upper portion of the stopper, and a cork in the upper open end of the cap and normally engaging the end of said extension, whereby the stopper is retained 70 in closed relationship with respect to the inner bottle. 75

In testimony whereof I affix my signature in the presence of two witnesses.

DOMENICO MOLINARI.
